TABLE CONSTRUCTION

Michael A. Wilkinson, Owego, N. Y., assignor to
Stakmore Co., Inc., New York, N. Y., a corpora-
tion of New York

Application August 2, 1940, Serial No. 349,453

2 Claims. (Cl. 311—96)

This invention relates to furniture and particularly to furniture of the folding type. More particularly the invention relates to extensible tables provided with folding legs, which tables are capable of being stored in a relatively small space when not in use.

Folding tables, that is tables with folding legs, are of course old in the art as are extensible tables with folding legs. However, the prior art tables of which I am aware all possess certain disadvantages, such as folding leaves, hinged tops and general instability due to the fact that the table legs do not support the outermost corners of the table when it is extended.

My invention provides a folding leg extensible table which may be used as a conventional four-place table when it is not extended, but which may be extended to provide a six-place table as required, and which, when so extended has the legs thereof at the outermost corners of the table, thereby providing a maximum of stability together with the greatest possible seating space and leg room for the occupants or users of the table.

My improved table, when extended, offers substantially twice the top surface area of the table as compared with its contracted position. Another important feature of my invention is that the table may be extended into its complete usable position by a single motion of the operator, and likewise, when the table is to be contracted, it is necessary only to raise one top section a distance sufficient to clear the other top section and push the two sections together, whereupon they automatically latch to provide a substantially square table of the type ordinarily used for card playing and similar purposes.

Another object of the invention is to provide an improved slide mechanism for an extension table, which slide mechanism will fold compactly and will at the same time permit the table top to lie perfectly flat and horizontal when the table is extended.

Still another object is to provide a slide mechanism adapted to cooperate with a hinged table top section, which top section is also capable of being lifted a limited distance vertically to accommodate the other top section thereunder when the table is contracted.

Other objects and advantages of the invention will be readily apparent from the following description and accompanying drawings wherein:

Fig. 1 is a bottom plan view of a table made according to my invention, with the major por-

tion of the legs omitted for clarity. The table is here shown in the folded or contracted position.

Fig. 2 is a perspective view taken substantially on the line 2—2 of Fig. 1 in the direction of the arrows, and showing details of the hinge mechanism for one top section.

Fig. 3 is a bottom plan view showing a latching mechanism for the two table top sections when the table is extended.

Fig. 4 is a section taken on the line 4—4 of Fig. 3.

Fig. 5 is a bottom plan view of the table in its extended position, the major portion of the legs being omitted for clarity.

Fig. 6 is a side elevational view of the table in its extended position.

Fig. 7 is a section taken on the line 7—7 of Fig. 1 showing details of the slide mechanism.

Fig. 8 is a fragmentary vertical section showing details of the folding leg mechanism.

Referring to the drawings, wherein like numbers denote like parts, 10 and 11 indicate a pair of three-sided frame members which are extensibly connected by a pair of slide assemblies 12 and 13 which will be hereafter described. A top member 14 is rigidly attached to the frame member 11 and additional rigidity of the top member 14 is ensured by a pair of transversely extending bracing members 15 and 16 which are secured to the edges and underside of the top member 14 by any suitable means such as screws or by glueing.

A top member 17 is pivotally attached to the other frame member 10, by a pair of spaced hinges 18, one of which is shown in detail in Fig. 2. Each hinge 18 comprises an L-shaped member 19 having one of its arms 20 rigidly attached to the frame 10, and the other arm 21 projecting inwardly toward the center of the table. The arm 21 is provided with a vertical slot 22 for a purpose to be hereafter described. A generally Z-shaped strap 23 has a short horizontal arm 24 rigidly attached to the under side of top member 17. The strap then extends downwardly in a generally vertical direction 25, for a predetermined distance and then extends inwardly in a generally horizontal direction 26 and for a distance sufficient to overlap a substantial portion 50 of the brace 15 when the table is not extended. The horizontal portion 26 of strap 23 carries a transversely extending pin 27 which projects through the slot 22 in arm 21. The pin 27 may be provided with a head 28 for retaining the pin 55 in the slot. The pin 27 moves freely in the slot

22 and the construction is such that the table top 17 may be both tilted around the hinge 18 and also raised vertically for a distance determined by the length of the slot 22. This distance should be such that the table top section 14 can be freely disposed under the top section 17, when the table is in its collapsed position.

When the table is extended and the two top members 14 and 17 lie in the same horizontal plane as shown in Fig. 5, they are maintained in alignment and against accidental displacement by one or more devices, here shown as two in number, each comprising a strap 30 attached to the top member 14 and carrying at its projecting end a pin 31 which projects into a recess 32 provided in the top member 17 near its edge.

Each of the frame members 10 and 11 carries two foldable table leg assemblies 33. The particular leg assembly here employed forms no part of the present invention, per se, and is fully described in Patent No. 1,776,346 issued Sept. 23, 1930, to C. A. Buffington. Briefly, each leg assembly comprises a rod 34 extending diagonally across the corner of the frame member and supported by the frame. A leg portion 35 is pivotally mounted on the rod 34. The leg portion 35 is preferably flat so that it will lie within the confines of the table when it is folded. When the legs are folded they lie diagonally across the under side of the table and within the limits of the frame members 10 and 11.

A latch 36 is pivotally attached to the adjacent frame member as at 37 and a spring member 38 tends to bias the latch 36 toward the table top. The outer end of the latch 36, which is notched, engages a pin 39 which extends across a slot 39a provided in the upper end of the leg member 35. The leg in Fig. 8 is shown in the unfolded position. When it is to be folded the projecting end of the latch 36 is released from the pin 39 and the leg 35 is then folded inwardly across the table and the latch itself, aided by the spring 38 assumes a substantially horizontal position with its outer end lying within the confines of slot 39a.

The table is latched when it is in its unextended or collapsed position, by means of a flat rod 40, which is pivoted as at 41 to the brace 15. One end of the rod 40 extends through the frame member 11 to provide an accessible handle portion 42 and the other end which is notched as shown at 43 extends beyond the inner edge of top member 14 for a distance sufficient to engage an L-shaped strap 44 attached to the under side of top member 17. A spring 45, attached to the rod and the brace 16, tends to bias the rod 40 normally toward its latching position.

The slide assemblies 12, 13, which permit the extension of the table a predetermined distance each comprises a member 50 fixedly attached to the inner side of frame member 10 and a similar member 51 attached to the braces 15, 16 of top member 14. Two additional members 52 and 53 have a tongue-and-groove connection with each other and with the members 50 and 51 respectively. The slide assemblies are shown in the extended position in Fig. 5 and in their collapsed position in Fig. 1. Limit stops are provided to limit the distance which each member of this assembly can slide relative to the other member. A slide assembly as herein described is not per se new, but I have found that when used with a folding table of the type just described wherein one top section overlies the other top section when the table is folded, the top surface of each

slide element should be tapered slightly, as shown in Fig. 6 to ensure a snug fit of the top sections when the table is folded or unextended. This tapered slide construction also permits the two top sections of the table to lie perfectly flat in the same horizontal plane when the table is in its extended position.

In the operation of my device, assuming the table to be in the collapsed position shown in Fig. 1, with the top section 17 overlying the top section 14, and the latch 40, 44 in the locked position, the table legs 35 are first unfolded so that they are vertical to the top sections. The table is then stood on its four legs and the latch members 40, 44 released. The table is then extended by drawing the frame 11 and its attached top section 14 and legs 35 away from the frame 10 and its pivoted top section 17 and legs 35. When the top section 14 is completely withdrawn from beneath the top section 17, the latter section, because of the hinge construction 18 drops into horizontal alignment with the top section 14 and is locked in place when the pins 31 enter the recesses 32. It will then be seen that when the table is extended as shown in Fig. 6, the four legs are disposed at the four outer corners of the table, thus ensuring the greatest possible stability and providing maximum leg room for the users.

To collapse the table it is merely necessary to raise the top section 17 and push the two top sections toward each other until the latch members 40, 44 engage each other. When the table is thus collapsed it affords a substantially square table of the type used for card-playing and similar purposes. When the table legs are folded in, the table is ready for storage, occupying but slightly more room than the conventional folding non-extensible card table.

While I have shown a specific embodiment of the invention, it is apparent that other forms might be adopted, provided they come within the scope of the following claims.

I claim:

1. An extension table comprising a pair of frame members, a top member supported by and attached to each of said frame members, one top member being attached to one side of its frame member, said top members lying one above the other when the table is unextended, a pair of foldable legs carried by each of said frame members, slide means separably connecting said frame members, said slide means comprising a plurality of interlocking and relatively movable members having tapered upper surfaces, said foldable legs being movable with each frame member to which they are attached whereby the legs support the table at its outermost corners when the table is extended.

2. An extension table comprising a pair of frame members, a top member supported by and attached to each of said frame members, means for pivotally attaching the outer edge of one of said top members to its corresponding frame member, said top members lying one above the other when the table is unextended, a pair of foldable legs carried by each of said frame members, slide means separably connecting said frame members, said slide means comprising a plurality of interlocking and relatively movable members having tapered upper surfaces, said foldable legs being movable with each frame member to which they are attached, whereby the legs support the table at its outermost corners when the table is extended.

MICHAEL A. WILKINSON.
